UNITED STATES PATENT OFFICE.

RALPH E. RILEY AND ROY B. WEIMER, OF AKRON, OHIO, ASSIGNEES TO THE MILLER RUBBER COMPANY, OF AKRON, OHIO, A CORPORATION OF OHIO.

INFLATABLE FIGURE TOY.

Application filed March 9, 1926. Serial No. 93,426.

Our present invention relates to inflatable toys. Reference is here made to our co-pending application #93,427, filed March 9, 1926.

5 The principal object of our invention is the provision of an inflatable toy made preferably from sheets of unvulcanized rubber and later vulcanized, which will have four legs simulating a quadruped, these legs to be 10 in their natural position. Obviously the invention is not limited to the production of quadrupeds, as bipeds may likewise be produced.

In such toys it has long been a problem as 15 to what method of manufacture to follow so that the legs will occupy their normal and natural position and at the same time not involve a complicated and expensive method or intricate and costly machinery.

20 To this end our invention comprises generally superimposing upon each other, two sheets of unvulcanized rubber or other suitable material, cutting these sheets to the shape desired either before or after superimposing them, seaming the edges so as to form a single inflatable compartment which will include the simulation, in a quadruped, of a head, two bodies and two sets of limbs. After seaming and vulcanizing the sheets,

25 one body is then folded upon the other so that they and the two sets of limbs register, and then they are cemented or otherwise secured to hold the two bodies in this position.

30 A tail, if the object simulated has a tail, may be provided in one of the bodies to increase the realism of the imitation. A valve 35 may be then placed in a limb, tail, or at any other place through which the toy may be inflated or deflated, as desired.

40 It will be noted in the specific embodiment of this invention that the head portion forms a part or an extension of one of the bodies, that is, it rises or extends from a point other than the symmetrical center of 45 the cut out figure. As such, when the bodies are folded, the head or the sheets of material forming the head lie in planes substantially parallel to the sheets of material forming the bodies.

50 The invention consists further in the novel construction, combination and arrangement of parts hereinafter described and shown in the drawings.

In these drawings:

Figure 1 is a plan view of the completed 55 article.

Fig. 2 is a sectional view along the line 2-2 of Fig. 1.

Fig. 3 is a view of the article before folding. 60

Fig. 4 is a sectional elevation along the line 4-4 of Fig. 3.

Fig. 5 is a detail of the valve element.

Fig. 6 is a side elevation of a modified 65 form of device.

Fig. 7 is a sectional elevation along the line 7-7 of Fig. 6.

Fig. 8 is a view of the article of Fig. 6 before folding.

Fig. 9 is a sectional elevation along the 70 line 8-8 of Fig. 8.

Referring to the embodiment shown, the 75 numeral 1 indicates a sheet of material such as unvulcanized rubber, and 2 a second sheet of the same material superposed thereon. From these sheets there is then cut a figure 80 simulating the animal to be imitated, such as by the use of a blunt knife or die, as is well known in this art. Such cutting or dieing serves to seal the edges of the sheets so that upon vulcanization this seam becomes permanent.

It will be noted that such cut out figure comprises two substantially symmetrical bodies 3 and 4, each having its own limbs 5 85 and 6, and a head 7 rising from a point substantially out of the symmetrical center of the bodies 3 and 4. The sheet 2 may be ornamented in any manner depending upon the 90 object to be imitated. In the form referred to the profile of the face will coincide with one of the edges of the head.

A tail 8 forms an extension of one of the bodies 4 to more nearly simulate the animal 95 desired.

In order to complete the animal toy, one body 3 is now folded upon the other body 4 so that the outlines thereof and the corresponding limbs substantially coincide. Any desired material or substance, such as cement, may be utilized to secure the two bodies in such superimposed position, the limbs remaining unattached to each other.

A valve such as may comprise a cylindrical member 9 held in one of the limbs 5 100 as by a rubber band, is provided and closed

by a plug 10 which may be removed when it is desired to inflate or deflate the toy.

It will be seen that upon inflation of the toy the two bodies appear as one, but four distinct limbs are provided which effectively simulate a quadruped in the form illustrated, the head of the animal rising from the proper place on the composite body.

Having thus described our invention, what we claim is:—

1. An inflatable toy comprising a single inflatable compartment and including a head, two bodies, and two sets of limbs, the two bodies being superimposed upon each other and their meeting sides secured together.

2. An inflatable toy comprising a single inflatable compartment, and including a head, two bodies, and two sets of limbs, the two bodies being superimposed upon each other and their meeting sides secured together, the head extending from one of the bodies.

3. A toy comprising a single compartment and including a head, two bodies, and two sets of limbs, the two bodies being superimposed upon each other and their meeting sides secured together.

4. An inflatable rubber toy comprising a single compartment including a head, two bodies and two limbs on each body, the

bodies and limbs being superimposed, the meeting sides of the bodies being secured together.

5. An inflatable toy, comprising a composite four-walled article having two bodies juxtaposed and secured together, a set of limbs depending from each body, a head upstanding from one of said bodies, and means to commonly inflate said parts.

6. A toy comprising an inflatable compartment folded upon itself so as to form a composite four-walled body having two adjacent inter-communicating portions, the adjacent walls of said portions being secured together, two legs depending from each portion, a head upstanding from one of said portions, and means to commonly inflate said parts.

7. An inflatable toy comprising a composite four-walled body having the two inner walls secured together, a head rising from one outer and one inner wall, two limbs depending from one outer and one inner wall, and two other limbs depending from the other inner and outer walls, and means to commonly inflate said parts.

In testimony whereof, we affix our signatures.

RALPH E. RILEY.
ROY B. WEIMER.
